ATTORNEY

UNITED STATES PATENT OFFICE.

GEORGE H. MAHAN, OF KANSAS CITY, MISSOURI.

OIL-BURNER.

1,392,187.

Specification of Letters Patent. Patented Sept. 27, 1921.

Application filed February 16, 1920. Serial No. 359,065.

To all whom it may concern:

Be it known that I, GEORGE H. MAHAN, a citizen of the United States, residing at Kansas City, in the county of Jackson and 5 State of Missouri, have invented certain new and useful Improvements in Oil-Burners; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to oil burners and particularly to a system of distribution from the source of supply to the source of consumption, as well as to means for controlling the supply flow under varying conditions.

20 According to the embodiment of the invention used for the purpose of illustration I have shown a burner normally supplied from a gas main or pipe, the flame from which is adapted to ignite the oil supply 25 from a separate main or pipe so that in the event that the gas supply is insufficient to raise the temperature of the atmosphere to the desired degree, oil may be admitted and burned to augment the heat generated from 30 the gas main and I have provided means whereby the introduction of the oil into the burner may be automatically responsive to variations in the temperature of the atmosphere.

35 I have also provided means whereby an excessive amount of oil introduced into the burner will be instrumental in cutting off the supply of oil so that flooding of the burner and an overflow therefrom will be 40 avoided.

In the drawings,

Figure I is a perspective view of a system contemplated by my invention and installed in connection with a furnace, the furnace 45 wall being broken away to show the interior construction thereof.

Fig. II is a detail view of the cut-off valve for the oil pipe and the means for controlling the actuation of the valve in the 50 normal position of the same, and

Fig. III is a detail view of the cut-off valve for the oil pipe shown in Fig. II.

Referring now to the drawings by numerals of reference:

55 1 designates a pipe which leads to a suitable source of gas supply (not shown), and

discharges into the hollow base 2 of an oil and gas burner, the particular construction of which is immaterial but may be generically described as consisting of the pan-shaped base 2, having vertical air openings 3 and 4 communicating with a conduit 5 provided with a central, downwardly directed discharge 6 whereby sufficient oxygen may comingle with the gas or oil to promote combustion.

7 is a pipe, leading from a suitable source of oil supply and provided with a valve 8, having a lever handle 9, at the respective ends of which are flexible connections 10 and 11 adapted to be actuated by suitable mechanism in a thermostat 12 of approved construction, controlled from a thermometer 13 in a manner well understood by those familiar with such devices.

Obviously, when the temperature affects the active element in the thermometer 13 in one direction, the valve 8 will be opened and when the active element is affected in an opposite direction, the valve 8 will be closed, 80 the device 12 being arranged so that a drop in temperature will open valve 8 and a rise in temperature will close it. It will, therefore, be apparent that the gas flame which is normally lighted will supply sufficient 85 heat to the furnace unless the temperature drops below a determined degree. Then the thermostat mechanism 12 becomes active to open the oil valve 8 and supply oil to the burner base 2 through the pipe 7. It may 90 be, however, that the thermostat will open the valve too wide; in which event an excess amount of oil would be introduced into the pan or base 2, and unless some means is provided for cutting off the supply or taking 95 care of the surplus oil, the bottom of the furnace would become flooded, with disastrous results.

In order to eliminate the probability of over-flowing of the burner, I have provided a discharge pipe or conduit 14, leading from the pan or base 2 and provided with a discharge end or nozzle 15 adapted to discharge into a bucket or receptacle 16, hung upon a lever 17 by a bail 18.

The lever 17 is shown as pivoted at 19 to the rigid outstanding arm 20 on the valve shell 21 so that it may swing with the bucket and permit the valve in pipe 7 to unseat the valve on stem 23. The valve on stem 23 is normally open but it is adapted to seat under the influence of the spring, one end

of which bears against the valve shell or casing 21 and the other end of which bears against the collar 25 rigid upon said stem. The arm 26 is rigid on the stem and it is connected to the downwardly curved extension 27 of lever 17 by a link 28, the lower end of which is outwardly curved as at 29 and connected to the extension 27 by a pivot 30, the connection of the upper end of the link 28 with the arm 26 being provided by the pivot 31. There is a set screw 32 in the extension 27 of the lever 17 to limit the upward swing of the arm 17, the end of the set screw 32 being adapted to abut against the link 28 as shown in Fig. II.

When the parts are assembled as illustrated in Figs. I, II and III, the valve in casing 21 will be opened, affording free passage of oil through the pipe 7. If, however, during the time that the valve on stem 23 is open, an excess of oil accumulates in the base 2, the oil will overflow and pass from the pipe 14 into the bucket 16. When there is a determined accumulation of oil in the bucket, the spring will be free to cause the seating of the valve. By reference to Fig. II, it will be observed that the valve is in its normal position, that is, it is in its open position, and it will remain so against the action of the spring so long as a straight line drawn through the pivots 31 and 30 cleave the pivot 19 because the force of the spring will not be sufficient to swing the pivot 30 to the right of pivot 19. When the bucket becomes supplied with a determined quantity of fluid, however, its weight will be sufficient to move the arm 17 on pivot 19 so that pivot 30 will be thrown to the right of the center of the pivot 19 carrying with it the link 28, which may rock on pivot 31. As soon as this is accomplished, the expansive force of the spring 24 may become effective in seating the valve.

It will be apparent from the foregoing that the zone to be heated may be maintained at practically a constant temperature because when the temperature drops, the valve 8 in the pipe 7 will open to admit oil and when the temperature rises, the supply will be reduced or ultimately cut off.

Of course, with a system such as described here, the valve 8 would open after the gas

flame from the pipe 1 was extinguished or even when it was not desired to have a fire in the furnace, but no ill effects would result because just as soon as the oil overflowed into bucket 16, the valve 21 would close to cut off further communication through said pipe so while valve 8 would be open, the safety cut-off valve would be closed and thereby obstruct the flow of the oil.

What I claim and desire to secure by Letters-Patent is:

1. A valve casing having a valve stem projecting therethrough, a lateral arm on said casing, a lever having a curved extension at one end and a weight at the other, means for pivoting the curved extension intermediate its ends to the arm, an arm on the valve stem, a link, one end of which is pivoted to the second mentioned arm and the other end of which is pivoted to the curved extension of the lever at one side of the pivotal connection between the lever and the first named arm, and means normally urging the valve to open position.

2. A valve casing having a valve stem projecting therethrough, a lateral arm on said casing, a lever pivoted to the lateral arm and having a curved extension projecting to one side of the pivot, a link connection between the valve stem and the end of the curved extension, a spring for normally urging the valve to open position, and an adjustable screw carried by the extension and having one end projecting against the link.

3. A valve casing having a valve stem projecting therethrough, parallel arms, one on the valve casing and one on the valve stem, the arm on the casing projecting beyond the arm on the valve stem, a lever pivoted intermediate its ends to the arm on the casing and having a curved extension projecting outwardly from the end of the arm on the casing, a link connected to the arm on the valve stem and having a curved end connected to the end of the curved extension on the lever, a bucket connected on the free end of the lever, and a spring normally urging the valve stem in one direction.

In testimony whereof I affix my signature.
GEORGE H. MAHAN.
